NECKTIE RACK

Sam Sampson, Hewlett, N. Y., assignor to Swank,
Inc., a corporation of Delaware

Application July 12, 1949, Serial No. 104,330

1 Claim. (Cl. 211—100)

1

This invention relates to a neck tie rack for holding a number of neck ties in a position which will enable them to be more readily viewed.

Neck tie racks are usually in a form which extend outwardly from the wall and comprise a bar over which the neck tie may be hung. When a number of ties are positioned on such a bar, the upper ties obscure the ones beneath and must be moved in order for one to see the under ties on the rack.

One of the objects of this invention is to provide a tie rack in which the ties may be more spread out and may be assembled in a position where they will not readily slide to one side or the other.

Another object of this invention is to provide a tie rack which may project from the wall or inside of a door to spread the ties for easy viewing, but which when not in use may be folded against the wall to dispose the ties one on the other for more compact storage.

Another object of this invention is to provide a simple form of construction by which the ties may be supported and yet held in ready view.

With these and other objects in view, the invention consists of certain novel features as will be more fully described hereinafter and pointed out specifically in the appended claim.

Figure 1 is a perspective view of the tie rack mounted on a wall in its collapsed position.

Figure 2 is a side elevation illustrating the tie rack in extended position and away from such support.

Figure 3 is a plan view of a bracket as blanked from sheet stock, which is used for pivotally mounting the arm of the tie rack, and Figure 4 is a sectional view through the bracket and arm showing the holding means for maintaining the two parts in a desired relative position.

In proceeding with this invention, I provide a U-shaped bracket between the spaced ears of which an arm is pivotally mounted. The arm carries bars over which different ties may be positioned, with some sort of spacing means for these ties to prevent them from sliding along the bar. A means is provided for holding the arm in a generally vertical position and another means for holding the arm in a generally horizontal position, the latter of which permits the ties to be more readily viewed while the former collapses the ties, one upon the other, for storage.

With reference to the drawings, the bracket is designated generally 10, as shown in the plan view in Figure 3 prior to being bent. This bracket is bent into generally U form to provide ears 11

2

connected by a wall engaging portion 12, having openings 13 for securing the same to the inside of a closet door, or wall 14. An arm 15, which has a width equal to the distance between the ears 11, is pivoted by a pin 16 extending through openings in the ears 11 and arm 15, and is headed at the outer surface of the ears so as to pivotally mount this arm in the bracket.

The arm 15 is usually formed of wood and is provided with a pair of bores 17 and 18 extending laterally across the arm 15. These bores contain balls 19—19 in the bore 17 and 20—20 in the bore 18, each of which pair are forced outwardly by springs 21 and 22, as shown in Figure 4.

There are a series of openings in the ears 11, there being a center opening 25 and openings 26 and 27 at either side, although positioned along the surface of an arc struck from the pivot opening 28 through which the pin 16 extends. When the arm is in the horizontal position, as shown in Figure 2, the balls 20 will extend into the openings 26 in the opposite ears, and the balls 19 will extend into the openings 25 in the opposite ears, as shown in Figure 2. When the arm is swung to the vertical position, the arrangement is such that the balls 19 will extend into the openings 27 to hold the arm in vertical position, and as the vertical position does not require as rigid a holding as the horizontal position, the spacing between the openings 27 and 25 is of a distance shorter than the distance between the bores 17 and 18 so that the balls 20 press against the ears but not into the openings 28 when the arm is in vertical position. It thus becomes a very easy matter to swing the arm from vertical position upwardly to where it is held more firmly by reason of the engagement of two pairs of balls than to swing the arm from the horizontal position downwardly to the vertical position when it is engaged by the two pair of balls in the interfitting openings.

A series of bars 30 of any desired number, the number shown being four, are provided, each of which has fingers 31 extending at right angles to the bar so as to receive neck ties, such as at 32, 33, etc., in the spaces between the fingers 31.

When the rack is entirely filled with neck ties, one in each of the spaces between the fingers 31, and draped over the bar, as shown in Figure 1, the rack may be disposed in a vertical position so that the neck ties will take up very little space while being packed closely together. However, when the arm is swung to horizontal position, as shown in Figure 2, the neck ties, as illustrated in dotted lines, will then be spaced apart, making

them readily observable and available for withdrawing from the rack.

I claim:

A necktie rack comprising a bracket adapted to be secured to a wall and provided with ears extending outwardly from the wall engaging portion thereof, an arm positioned between and pivotally mounted by said ears, a crossbar carried by said arm over which ties may be positioned, a plurality of pairs of spring pressed balls carried by said arm and urged outwardly toward said ears a spaced distance apart, said ears having openings with at least a pair of openings in each ear being spaced the same distance as said balls and located to receive a pair of balls when the arm is in horizontal position and another opening in each ear is positioned a different distance from any other opening than the distance between a pair of balls and is located to receive a single ball when the arm is in vertical depending position

whereby less force is required to detach the balls from locking position when the arm is vertical than when horizontal.

SAM SAMPSON.
